UNITED STATES PATENT OFFICE.

HENRY J. MERLE, OF CHICAGO, ILLINOIS.

DESIGN FOR A DESK.

44,770.

Specification for Design.

Patented Oct. 21, 1913.

Application filed July 2, 1913. Serial No. 777,093. Term of patent 14 years.

To all whom it may concern:

Be it known that I, HENRY J. MERLE, a citizen of the United States, residing at Chicago, in the county of Cook and State of Illinois, have invented a new, original, and ornamental Design for Desks, of which the following is a specification, reference being had to the accompanying drawing, forming part thereof.

The figure is a perspective view of my new design for a desk.

I claim:

The ornamental design for a desk as shown.

HENRY J. MERLE.

Witnesses:

CHARLES O. OLSON,
C. O. BOWERS.
